GREASE GUN FILLER

Mathias Schwabenlender, Hilbert, Wis.

Application August 24, 1937, Serial No. 160,695

3 Claims. (Cl. 221—47.5)

This invention relates to grease gun fillers and has for the primary object the provision of a device of this character in which a conventional type of grease gun may be conveniently positioned and held and may be easily actuated to fill the grease chamber of the gun solidly with grease and thereby eliminate air pockets within the grease of the gun and permit the gun filling operation to be quickly carried out without waste or loss of grease or the soiling of the hands of the operator, the device being so constructed as to receive a large amount of grease from a container and to maintain the grease free of foreign matter.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a grease gun filler constructed in accordance with my invention.

Figure 2 is a sectional view taken on the line 2—2 of Figure 1.

Figure 3 is a sectional view taken on the line 3—3 of Figure 2.

Figure 4 is a sectional view taken on the line 4—4 of Figure 2.

Figure 5 is a sectional view taken on the line 5—5 of Figure 1.

Figure 6 is a sectional view taken on the line 6—6 of Figure 2.

Figure 7 is a fragmentary side elevation illustrating a modification of my invention.

Referring in detail to the drawings, the numeral 1 indicates a gun supporting sleeve having an opening in one side thereof to permit easy and quick application and removal of a conventional type of grease gun from the sleeve. A semi-circular shaped support 2 is arranged in the sleeve 1 and may be adjusted vertically for a limited distance so as to accommodate guns of different sizes in the sleeve 1. The seat 2 has the discharge end of the gun brought in engagement therewith, as clearly shown in Figure 2, positioning the filling end of the gun uppermost and the sleeve adjacent thereto is offset, as shown at 3, to prevent the screw threads on the filling end of the gun from contacting with the sleeve and becoming damaged thereby. When the gun is placed in the sleeve 1 the cap for the filling end of the gun is removed.

Integral with the upper end of the sleeve 1 is a valve housing 4 composed of detachably connected sections and one section is integral with the sleeve 1 and the other section integral with a grease hopper 5. A ball type valve 6 is rotatably mounted in the housing 4 and is equipped with a stem 7 carrying a finger piece 8 arranged exteriorly of the housing whereby the passage 9 for the valve element may be moved into and out of registration with the grease hopper 5 and the sleeve 1. The hopper 5 is of substantially hopper-shape and the receiving end thereof may have a grease container, when inverted, positioned thereover so that the grease of the container may pass into the hopper. The receiving end of the hopper has secured thereto a blade 10 for contact with the bottom of the hopper and act as a scraper to remove any grease adhering to the bottom of the container by rotating the latter relative to the hopper. The blade 10 has a compound curve, as shown in Figure 4.

The lower end of the sleeve 1 is reduced and threaded in a pipe or tube 11 carrying at its lower end a hardened strike element 12. Received in the pipe or tube 11 is a rod 13 secured on a base 14. The base 14 acts as an anvil for the strike element to engage and the rod 13 acts as a guide for the movement of the device in an upward and downward direction.

Instead of employing the base 14 a base 15 may be used and consists of an L-shaped portion having an attaching flange 17 for securing the base onto a wall or like support with its striking flange or face 18 disposed uppermost and carrying the rod 13.

In operation, after the placing of a grease gun in the sleeve 1 the valve is actuated to connect the hopper with the upper end of the sleeve. The operator then moves the sleeve 1 upwardly and downwardly or, in other words, reciprocates the sleeve 1 in a vertical path and as the strike element 12 engages the base a jolting effect will be imparted to the gun for the purpose of causing the grease to pass therein and to settle solidly in the gun and thereby eliminate air pockets forming in the grease and assure complete filling of the gun with grease. After the filling of the gun or discontinuance of the use of the device the valve is closed, preventing the escape of the grease from the hopper. It will be seen that a grease gun can be conveniently and quickly filled without soiling the hands of the operator and further that the hopper may be conveniently filled with grease from a grease container.

What is claimed is:

55

1. A grease gun filler comprising a supporting sleeve to receive and support an open grease gun, a grease hopper connected with said sleeve, a valve for controlling the flow of grease from the hopper to the gun within the sleeve, and means for slidably supporting said sleeve whereby the latter may be reciprocated and subjected to a jolting action for settling grease in the gun.
2. A grease gun filler comprising a gun supporting sleeve having an entrance in the side thereof, a seat adjustably mounted in said sleeve to be engaged by a gun, a grease hopper connected with said sleeve, a valve for controlling the flow of grease from the hopper to the sleeve, a pipe connected with the sleeve, and a guide slideable in said pipe and providing an anvil for the pipe to strike and thereby impart a jolting action to the gun.
3. A grease gun filler comprising a gun supporting sleeve, a hopper connected with said sleeve, a valve between said hopper and sleeve, a pipe connected to said sleeve, a rod slidably received by said pipe, and a base for supporting said rod and acting as an anvil to be struck by said pipe and thereby impart a jolting action to the gun. 5 10
